(57) **CLAIM**

The ornamental design for a pair of removable eye inserts, as shown and described.

DESCRIPTION

FIG. 1 is a front view of one of the pair of eye inserts. FIG. 2 is a side view of one of the pair of eye inserts. FIG. 3 is a top view of one of the pair of eye inserts. FIG. 4 is a view from the back of one of the pair of eye inserts; and, FIG. 5 is a view of the eye inserts as they are placed over the eyes of a person. The person is shown in phantom dashed lines.
